UNITED STATES PATENT OFFICE.

JOHN DENNIS, OF OSWEGO, NEW YORK.

RAILWAY-BRIDGE.

SPECIFICATION forming part of Letters Patent No. 319,798, dated June 9, 1885.

Application filed May 27, 1882. Renewed September 3, 1884. (No model.)

To all whom it may concern:

Be it known that I, JOHN DENNIS, a citizen of the United States, of the city of Oswego, in the county of Oswego and State of New York, now temporarily residing at the city of Toronto, in the county of York, in the Province of Ontario, Canada, have invented certain new and useful Improvements in the Construction of Railway-Bridges, of which the following is a specification.

The object of the invention is to construct an extremely strong and rigid railway-bridge not susceptible to rot and having a fire-proof deck to prevent live coals falling from a locomotive taking effect; and it consists of a peculiar arrangement of peculiarly-constructed trusses designed to give the greatest possible strength, and arranged so that the joints are all protected from water, while the main timbers are arranged so that air will circulate freely around them.

While the principal feature in my invention consists in the peculiar arrangement of three or more separate trusses placed below each rail, I shall first proceed to describe the construction of a single truss and afterward indicate the manner in which they are combined together to form compound trusses.

Figure 1 is an elevation of my improved bridge. Figs. 2 and 3 are sections at the center and at the end, respectively. Figs. 4 to 15 are details of the various portions of the bridge, which it is important to have clearly shown.

In the drawings, A is the lower chord, designed to rest upon the pier or posts B.

C is a central arched chord made in sections securely spliced and bolted together, notches a being formed on the upper and lower faces of the timbers bolted together to prevent any longitudinal movement of the parts so bolted together, thereby relieving the strain which would otherwise be directed against the bolts.

D are a series of diagonal braces extending, as indicated in Fig. 1, from the straight or lower chord, A, to the central arched chord, C, into which they are securely boxed, as indicated, the diagonal braces over the piers being of heavier material than the braces near the center of the bridge.

E are counter-braces extending from the top of one diagonal brace to the bottom of the next brace and placed, as indicated, so that

one-half of their ends shall rest against the diagonal braces, while the other half fit, respectively, against the arched and lower chords.

F are bolts extending from the arched chord C to the straight chord A, and situated outside of and parallel with each counter-brace. These bolts hold the parts securely together and complete a single truss.

G is an upper or carrying chord supported from the arched chord by the diagonal braces H. These braces, it will be noticed, extend from the outer end of the arched chord, and are designed to direct the strain of the load toward the outer side of the pier.

The bolts I extend diagonally from the top of the upper chord between the arched chord and through the clamp-pieces J. These clamp-pieces are situated so that the strain on the bolts will cause the clamp-pieces to press the counter-braces against their respective diagonal braces and are designed to hold the trusses together and brace the three trusses marked 1, 2, and 3 in Fig. 2, which are formed in the manner of the truss hereinbefore described.

Wherever it becomes necessary to form a splice in the lower chord, A, I provide what may be termed a "tie-piece," K, notched on its lower surface, as indicated, which notches fit into corresponding notches formed at this point on the top surface of the lower chord, A.

It being important, I should mention here that the tie-pieces should be sufficiently long to take in a distance between three of the main bolts F, by which means the load on the bridge has a tendency to strengthen the splice. Bolts L are provided to secure or clamp the tie-piece to the lower chord.

In the center of the bridge, where the angle of the diagonal braces is reversed, it is necessary to provide a cast-iron prism, M. This prism is formed substantially as shown in Fig. 10, in which figure it will be noticed that on either side of the prism M a curved lip, n, is provided to form a gutter to direct the water clear of the timbers. On each end of the prism M is formed an apron, n, designed to lap over the tie-pieces K, upon which it is set. The top of this tie-piece is covered with galvanized iron, the ends of which, coming against the prism M, are turned up below the lips n to form a gutter and prevent any water falling

off the lips finding its way between the prism M and the timbers upon which it is set, thereby forming a water-tight joint.

In order to still further insure a water-tight joint, I form on the top of the prism M a socket or stuffing-box, p, around each of the holes through which the bolts F pass. These stuffing-boxes are filled with pitch, tar, or other suitable composition.

10 In order to provide a support between the pier and the bottom chord of the bridge which will not be susceptible to dry rot, I provide a series of open posts constructed in the following manner: The sills O lie on top of the pier 15 B', a space being left between them. Beams O', corresponding with the sills O, are provided below the chord A. Between the sills O and beam O', I arrange a series of posts, P, around a short block, P'. This center block is bored out in its center and has vertical grooves cut around its outer surface to permit the air to pass freely between all the outer posts, arranged as described. The center block, P', does not extend to the bottom of the 5 sills O, so that there is a space between the bottom of the post and the top of the pier, to admit the air.

In order to exclude the moisture from the earth which abuts against the approach to the bridge, I provide a plank weather-board or apron, Q, as shown in Fig. 1. This effectually protects the ends of the timbers forming the approach to the bridge, and in the winter, when the earth is frozen, in heaving of the earth by the frost at the approach, the end of the approach is correspondingly raised, owing to the connection formed by the weather-planking, and consequently the level of the rail on the bridge will be the same as that on the embankment at the approach.

As shown in Figs. 2 and 3, the arrangement of my compound truss forming a support under each rail is indicated. The single trusses between the lower chord, A, and arched chord C are arranged, as shown in Figs. 2 and 3, immediately below the point where the rails P will be located.

In order to brace together the compound trusses formed by the single trusses, I arrange a series of transverse beams, Q', on top of the arched chord C and corresponding transverse beams on the bottom of the lower chord, A. These transverse beams are bolted together by the bolts F, said transverse beams being placed at each point in the truss where the bolts pass through.

In order to stay the compound trusses thus braced together, and to prevent the swaying thereof, I make the transverse beams Q' project beyond the compound trusses to the full width of the bridge to be built, and arrange diagonal braces R, as indicated in Figs. 2 and 3.

Fig. 2 represents a section of the bridge at its center. At this point the braces R extend from the bottom of the inner truss to the outside end of the top transverse beam Q', while

the braces R' extend from the top of the inner truss to the outside of the bottom transverse beam Q.

In order to complete the bridge thus constructed, I connect the upper and lower transverse beams Q by the bolts S, which spring the ends of the beams together and impart a tightening strain against the braces and trusses. 70 75

In the former part of the specification I describe the manner of connecting the carrying-chord G upon the arched chord. It will of course be understood that this portion of the construction of the bridge will be erected on 80 the lower truss after the complete compound trusses have been put together, as herein described, and placed in position clear of the scaffold.

The deck, as indicated, is composed of narrow planking extending from side to side of the bridge, and sprung to form a curved deck, as indicated in Figs. 2 and 3, the said form being produced in the following manner: Bolts U are put through the upper transverse beam 90 Q', and through the hand or guard rail d in Figs. 2 and 3, which rail is placed one foot higher than the top of the floor of the bridge. The planks are then put in place and an iron standard, e, is placed upon one end of said 95 planks and against the hand or guard rail. The other end is then bent down to the desired radius and the standard on the opposite side put in position. The pressure on the plank will embed the ends of the standard into the plank 100 and hold them firmly in position.

In Fig. 14 a detail is shown for supporting the hand or guard rail. This post is made of metal, and has notched or serrated ends which become embedded in the timbers when the 105 bolts U compress the rails to the deck. These planks are grooved and slip-tongued together and are covered with a composition of pitch or tar and gravel, thereby forming both a water-tight and fire-proof deck, the curved form 110 of the deck carrying any water falling on the deck clear of the bridge.

In order to prevent the lodgment of water or moisture on the deck between the track rails or stringers, I support the rail on a chair, 115 V, constructed and arranged as follows: As shown in Figs. 4 and 5, the chair V supports the rail slightly above the deck, leaving a space between each two adjacent chairs for the purpose of permitting the water to pass freely 120 away. In order to prevent the lodgment of water under the chair, I form on its bottom a channel or groove, u, connecting the bolt-holes. In order to permit the filling of this groove 125 with tar or pitch, I make other holes leading into the channel, through which the tar or pitch, when in a liquid condition, may be freely poured to fill the channel and prevent any water which might pass through the bolt-hole finding its way through to the deck. This, 130 however, I design to make the subject-matter of a separate application.

When the posts B are in an exposed position, and it becomes necessary, owing to their

length, to provide cross-braces or waling-timbers, I make the following provision for the purpose of protecting the joints from the lodgment of water: In Figs. 6 and 7 I show 5 an arrangement for accomplishing this purpose. In these figures, *d* is a metal bracket let into the post *B*, as shown in Fig. 6, and having a recess formed on its face to receive the end of the waling-timber *e*. It will be 10 noticed that a portion of the bracket let into the post *B* slants outwardly to the outside of the recess receiving the end of the waling-timber *e*, overlapping the joint and forming a 15 shed to conduct any water on the post *B* clear of the joint between it and the waling-timber.

When securing the waling timber or brace to the post, I provide a link or links, *f*, preferably placed one on each side of the post, as shown in Fig. 7, one end of the link *f* being 20 connected to the post *B* by a bolt passing through it and the other end of the link to the waling timber or brace by a similar bolt.

In order to prevent any water finding its way into the bolt-hole and thereby rotting the 25 timber and rusting the bolt, I enlarge the hole in the post through which the bolt passes and provide a washer, *g*, to cover either end of the said hole. A recess, *g'*, is formed on the top of the washer *g*, having a groove 30 around its outer surface (similar to the chair in Fig. 4) for the purpose of permitting liquid tar or pitch to be poured in the hole around the bolt, and thereby forming the desired seal to prevent the admission of water.

35 Wherever a joint is required in a horizontal timber which is exposed, I form a V-splice, as indicated in Fig. 8, and protected as shown in Fig. 9. In these figures it will be noticed that the washer *h* is embedded in the top surface of the timber immediately over the V-shaped joint, and that at each end of the washer a pin or spike point, *h'*, is formed. This spike-point constitutes a lock for securing the ends of the jointed timbers together, 45 while the V-shaped connection permits the lateral adjustment of the two timbers. In order to prevent any water finding its way below the washer or the bolt-hole, I fill in the space above the embedded washer with tar or 50 pitch, and in order to protect the entire surface of the timbers, including the joints, I spread tar or pitch and gravel.

Wherever a vertical timber butts against a horizontal timber in an exposed position, I 55 form a water-tight joint, as shown in Fig. 13. Instead of putting a mortise-and-tenon joint, I place a square hard wood pin in a round hole in the end of the vertical timber and bore a hole in the horizontal timber to receive its 60 projecting point.

In order to ventilate the center of the vertical post, I bore diagonal holes *k* in the center hole of the post. These holes *k* permit me to pour into the center hole tar or pitch, which 65 fills the space between the pin and hole, and also two grooves, *k'*, formed on the bottom end

of the vertical post, forming thereby a water-tight joint.

When the posts arranged to support the ends of the bridge are in an exposed position, I 70 insert a semicircular piece of galvanized iron, *O*, near the bottom of the post, and on either side of the said iron I place a plate, *O'*. By inserting the galvanized iron in the semicircular form it will remain in position better 75 than if it were straight. This galvanized iron forms a shed to receive the water trickling down the side of the post, and discharges it on the plates *O'*, which keep it away from the joint. 80

What I claim as my invention is—

1. In a bridge having a straight lower chord braced to a central arched chord by diagonal braces boxed into the straight and arched chords, the combination, with said chords and 85 braces, of counter-braces, the upper end of each being set so that one-half shall rest against the arched chord and its other half against one of the diagonal braces, the lower end of the counter-brace being similarly situated against 90 the straight lower chord and the bottom end of the next diagonal brace, and suitable bolts extending from the arched chord to the straight chord outside of and parallel with each counter-brace to hold the braces in position and 95 complete the single truss, as specified.

2. In a bridge having a central arched chord braced, as described, to the bottom or lower chord which rests upon the pin, the upper or carrying chord suitably braced to the arched 100 chord by diagonal braces extending from the outer end of the arched chord for the purpose of directing the strain of the load to the outer end of the truss, substantially as and for the purpose specified. 105

3. In a bridge having a central arched chord braced, as described, and the lower straight chord, and an upper or carrying chord braced to the arched chord by diagonal braces, the combination, with such chords and braces, of 110 bolts extending diagonally from the top of the carrying-chord to the bottom of the arched chord and held in position by clamp-pieces, substantially as and for the purpose specified.

4. In a bridge in which the carrying or upper chord is braced to the lower chord, as described, so as to form a complete single truss, three or more trusses so formed placed below each rail and braced or tied together by the transverse beams, in combination with the 120 diagonal braces *R* and bolts *F*, situated substantially as shown and described. 115

5. In a railway-bridge provided with a curved water-proof deck, a wooden hand-rail supported by the metal standards having 125 notched or serrated ends to fit into the hand-rail and deck, as described, in combination with the bolts extending from the top of the hand-rail through the standards and deck to the transverse beam, substantially as and for 130 the purpose specified.

6. In a bridge in which the length of the

chords necessitates their being spliced, a tie-piece notched on its bottom surface and placed over the joint on the top edge of each chord, which chord has corresponding notches formed 5 on its top surface, in combination with braces D E, bearing on the tie-pieces, bolts F, arranged to strain the whole together and allow the load on the bridge to assist in strengthening the splice, substantially as and for the purpose specified.

7. In a bridge in which compound trusses are placed below each rail and bound together by transverse beams located on the top and bottom of the trusses and projecting beyond 15 the trusses to the full width of the bridge, the combination, with such compound trusses and beams, of cross-braces extending from the top to the bottom transverse beams, which are drawn together at their outer ends by bolts S, 20 designed to spring the ends of the beams together and impart a tightening strain against the braces and trusses, as set forth.

8. In combination with two timbers the ends of which are connected together by a V-shaped joint, a washer, h, embedded in the 25 top surface of the timbers immediately over the V-shaped joint and having spiked ends h', to form a lock for connecting the ends of

the timbers together, the spaces above the washer being filled and top surface of the 30 timbers covered with a composition of tar or pitch and gravel, substantially as and for the purpose specified.

9. In a truss-bridge in which the center braces are supported on a metal prism having 35 aprons on either end to fit over the tie-piece and stuffing-boxes around the bolts, as described, curved lips formed on either side of the said prism, in combination with a galvanized-iron covering placed on top of the tie-piece supporting the prism, and having curved 40 ends fitting below the curved lips of the prism for the purpose of forming a gutter to receive any water falling from the prism, substantially as and for the purpose specified. 45

10. A short center block, p', having a hole bored in its center and vertical grooves cut in its outer surface, in combination with a series of posts, p, as described, for the purpose of forming a ventilated support to the ends of 50 the bridge, as specified.

JOHN DENNIS.
